UNITED STATES PATENT OFFICE

RALPH ROSE, OF BUFFALO, NEW YORK, ASSIGNOR TO FEDDERS MANUFACTURING COMPANY, INC., OF BUFFALO, NEW YORK

DESIGN FOR A LIQUID SERVING APPARATUS

Application filed April 10, 1933. Serial No. 47,739. Term of patent 14 years.

To all whom it may concern:

Be it known that I, RALPH ROSE, a citizen of the United States, residing at Buffalo, in the county of Erie and State of New York, have invented a new, original, and ornamental Design for a Liquid Serving Apparatus, of which the following is a specification, reference being had to the accompanying drawing, forming a part thereof.

In the drawing:

Fig. 1 is an elevation of the liquid serving

apparatus as viewed from the rear, or operator's side thereof.

Fig. 2 is a perspective view of the opposite side of the liquid serving apparatus on an enlarged scale, showing my new design.

I claim:

The ornamental design for a liquid serving apparatus substantially as shown and described.

RALPH ROSE,
